J. HOWE.

CORK AND BUNG CUTTER.

APPLICATION FILED JULY 15, 1909.

969,535.

Patented Sept. 6, 1910.

UNITED STATES PATENT OFFICE.

JOHN HOWE, OF NEW YORK, N. Y., ASSIGNOR OF ONE-HALF TO HIMSELF AND ONE-HALF TO JAMES BLUMER, OF NEW YORK, N. Y.

CORK AND BUNG CUTTER.

969,535.

Specification of Letters Patent.

Patented Sept. 6, 1910.

Application filed July 15, 1909. Serial No. 507,689.

To all whom it may concern:

Be it known that I, JOHN HOWE, a citizen of the United States, residing in East New York, in the county of Kings, city and State 5 of New York, have invented an Improvement in Cork and Bung Cutters, of which the following is a specification.

Heretofore in the manufacture of corks and bungs for bottles, casks and similar 10 liquid-holding vessels it has been usual to cut the same from the cork sheets with parallel sides and of true cylindrical form and then either again cut the corks or the bungs tapering in another and special manner, or compress the cylindrical cork at 15 one end prior to forcing the same into the neck of the bottle or other vessel. Corks and bungs for bottles, casks and similar liquid-holding vessels have also been cut 20 tapering out of the cork sheets by suitable sliding cutters.

The object of my invention is the provision of a revoluble cutter of special construction which shall at one operation cut 25 a cork tapering in form ready for use without further treatment.

In carrying out my invention, I provide a built-up revoluble head in part hollow and tapering, means for revolving the head, 30 a series of knives or cutters circularly arranged and means for slidably reciprocating the same axially of the head and other means for simultaneously guiding the knives or cutters over the surface of the 35 tapering head. A surrounding tapering sleeve encompasses the knives or cutters and serves to hold them in position. The place where the cutters protrude on the end of the head represents the maximum diameter 40 of the cork or bung being cut, and as the knives emerge they approach, contracting the diameter.

The device of my invention is to be made in various sizes according to the sizes of 45 the tapering corks or bungs to be cut.

In the drawing, Figure 1 is a plan and section through the sleeve representing the device of my improvement; the cutters being in their retracted position. Fig. 2 is a 50 similar plan and section with the cutters projecting. Fig. 3 is a longitudinal section also showing the devices for reciprocating

the cutters. Fig. 4 is a cross section at the dotted line x, x , of Fig. 2. Fig. 5 is a cross section at the dotted line y, y , of Fig. 3, 55 and Fig. 6 is an illustrative section showing the relation of the cutters as projected and in the act of cutting a cork from a strip against a foundation. The section Fig. 3 is taken approximately on the dotted line 60 z, z , of Fig. 5.

a represents the head stock. This is recessed at one end to receive the tubular spindle b , which in turn is connected to a suitable revoluble foundation not shown, for 65 the purpose of turning the entire cutting implement. The head stock a is reduced and exteriorly threaded and recessed and interiorly threaded at the opposite end.

I provide a tapering head c exteriorly 70 threaded at its larger end and screwing into the recessed portion of the head stock and within the larger end of the tapering head c a stop ring d is received and held. The tapering head is provided with spaced longitudinal slots 2, and e represents a tapering sleeve interiorly threaded at its larger end and screwing upon the reduced exteriorly threaded end of the head stock. Between the tapering head c and tapering sleeve e is 80 an annular recess receiving the series of knives or cutters f . These are of slightly curved cross section arranged slightly spaced apart in the retracted condition in Figs. 1 and 3, and adapted when projected as in 85 Fig. 2, to come together along their edges. The knives or cutters f of the series are each provided with a slot 3 receiving the head of a stud 4, the shank of which is secured in the tapering head c and these cutters are 90 each perforated for a bolt 5. These bolts 5 are of peculiar construction as will appear particularly from Figs. 3 and 5. Each one has a threaded portion which passes through the opening in the cutter and a nut 6 coming 95 against the outer surface of the cutter, and two shouldered portions; one shouldered portion coming against the under surface of the cutter in the slot 2 of the tapering head c in which this portion of the bolt is 100 parallel sided. The lower portion of the bolt is oppositely spread and shouldered as seen in Fig. 5 so that the lower shoulders come at opposite sides beneath the inner sur-

face of the tapering head *c*; therefore while the bolts 5 form guides in the slots 2 for the cutters *f*, outward movement of said bolts is prevented by the shoulders which come 5 against the inner surface of the head *c*.

Fig. 5 indicates that the several bolts or series are disposed radially with reference to the axial center of the cutting device.

I provide a rod *h* in the axial center of 10 the cutting device with a head *h*¹, and a sleeve *i* surrounding the rod fitting the apertured center of the head stock and the open center of the tubular spindle *b* and guided therein and this sleeve is provided with a 15 head *i*¹. This rod *h* and sleeve *i* are connected in a definite relation by a pin 7 so as to provide for the spacing apart of the head *h*¹ from the head *i*¹ and also providing for these heads coming at opposite sides of 20 the bolts 5. The rod *h* and the sleeve *i* consequently move together and are actuated by a lever *k* manually operated, or by an equivalent device which is adapted to impart reciprocating movements to the rod *h*, 25 sleeve *i* and their heads and in turn to actuate and reciprocate the series of cutters *f* from the retracted positions of Figs. 1 and 3 to the extended or projected relation shown in Fig. 4, and between which positions with the rapid rotation of the head stock and connected parts, the cutters have 30 passed through the slab or sheet of cork and cut therefrom a cork or bung of tapering form.

This device is preferably made in various sizes according to the size of the cork or bung which is to be formed, the same operating with one action and stroke in forming a cork or bung of tapering character.

40 I claim as my invention:

1. The combination with a revolute head stock, of a hollow tapering head connected therewith and longitudinally slotted, a series of knives or cutters circularly arranged upon 45 the surface of the hollow tapering head, means connected to said cutters and passing through the slots of the hollow head, and other means connected with the latter means providing for a reciprocation of said cutters 50 simultaneously with their revolution by the revolute head stock.

2. The combination with a revolute head stock, of a hollow tapering head connected therewith and longitudinally slotted, a series 55 of knives or cutters circularly arranged upon the surface of the hollow tapering head, means connected to said cutters and passing through the slots of the hollow head, other means connected with the latter means providing for a reciprocation of said cutters 60 simultaneously with their revolution by the revolute head stock, and an imperforate surrounding tapering sleeve inclosing the series of knives or cutters.

3. A cork or bung cutter, comprising a 65 head stock, a tubular spindle adapted to be revolved, a tapering head connected to the head stock and provided with spaced apart longitudinal slots, a series of knives or cutters circularly arranged around the tapering 70 head and also provided with spaced slots, studs secured in the tapering head and having parts received in the slots of the cutters, and bolts passing through the slots of the tapering head and connected to the series of 75 knives or cutters, and means adapted for longitudinal movement and for engagement with said bolts for reciprocating the said series of knives or cutters.

4. A cork or bung cutter, comprising a 80 head stock, a tubular spindle adapted to be revolved, a tapering head connected to the head stock and provided with spaced apart longitudinal slots, a series of knives or cutters circularly arranged around the tapering 85 head and also provided with spaced slots, studs secured in the tapering head and having parts received in the slots of the cutters, and bolts passing through the slots of the tapering head and connected to the series 90 of knives or cutters, an axially disposed rod and a surrounding sleeve connected together, and means for moving the same through the center of the head stock and tubular spindle, a head formed with said rod and another 95 head formed with said sleeve and spaced apart to come at opposite sides of said bolts, whereby a reciprocating movement is imparted to the series of knives or cutters.

5. A cork or bung cutter, comprising a 100 head stock, a tubular spindle adapted to be revolved, a tapering head connected to the head stock and provided with spaced apart longitudinal slots, a series of knives or cutters circularly arranged around the tapering 105 head and also provided with spaced slots, studs secured in the tapering head and having parts received in the slots of the cutters, and bolts passing through the slots of the tapering head and connected to the series 110 of knives or cutters, means adapted for longitudinal movement and for engagement with said bolts for reciprocating the said series of knives or cutters, and a surrounding tapering sleeve inclosing the series of 115 knives or cutters.

6. A cork or bung cutter, comprising a head stock, a tubular spindle adapted to be revolved, a tapering head connected to the head stock and provided with spaced apart longitudinal slots, a series of knives or cutters circularly arranged around the tapering 120 head and also provided with spaced slots, studs secured in the tapering head and having parts received in the slots of the cutters, and bolts passing through the slots of the tapering head and connected to the series of 125 knives or cutters, an axially disposed rod

and a surrounding sleeve connected together, means for moving the same through the center of the head stock and tubular spindle, a head formed with said rod and 5 another head formed with said sleeve and spaced apart to come at opposite sides of said bolts, whereby a reciprocating movement is imparted to the series of knives or

cutters, and a surrounding tapering sleeve inclosing the series of knives or cutters.

Signed by me this 15th day of June 1909. 10

JOHN HOWE.
